[57] CLAIM

The design for a receptacle rinser, as shown.

DESCRIPTION

FIG. 1 is a perspective view of a receptacle rinser showing my new design;

FIG. 2 is a rear plan view thereof;

FIG. 3 is a right side view thereof;

FIG. 4 is a left side view thereof;

FIG. 5 is a top view thereof; and,

FIG. 6 is a bottom view thereof.

The pipe and hose shown broken away in all views is understood to represent indeterminate length.
